UNITED STATES PATENT OFFICE.

HUGO JUNKERS, OF DESSAU, GERMANY.

FLYING MACHINE.

Application filed September 27, 1923, Serial No. 685,133, and in Germany October 2, 1922.

My invention refers to flying machines and its particular object is to provide means whereby more room is made available for useful loads without unduly interfering 5 with the mechanical strength of the hull of the machine.

In aircraft design great difficulties are experienced in giving sufficient strength to that part of the hull which is designed for 10 the useful load, inasmuch as it requires large free spaces and openings in the wall whereby the necessary bracing of the walls is frequently rendered impossible. This difficulty is enhanced in cases where the hull is only low in proportion to the dimensions of the loads to be accommodated. In such cases, it became necessary to enter the hull from above, inasmuch as, paying due regard to the necessary strength, it proved impossible to provide lateral entrance apertures communicating with the large upper opening of the hull.

The present invention is designed to provide for especially large free spaces within the hull in combination with lateral openings by utilizing the struts connecting the hull with the wing, such struts being reinforced correspondingly, as well as that portion of the wing which adjoins the hull, for bracing this latter. By this means essential parts of the usual supporting and bracing structure of the hull adjacent the wing can be dispensed with. Thus, for instance, the hull of an aeroplane having its 35 wing disposed high above and serving for bracing the hull can have a space for the useful load which is open on top and at the sides, the rigid system thus presenting gaps which allow entering the hull from 40 the sides. My invention further includes particular features embodied in the wing and the braces forming part thereof and which are utilized for bracing the hull in such manner that the combination of these 45 parts furnishes the necessary rigidity.

In the drawings affixed to this specification and forming part thereof, several forms of an aeroplane embodying my invention are illustrated diagrammatically by way of 50 example. In the drawings—

Fig. 1 is a diagram showing in vertical longitudinal section a high-winged aeroplane with the hull and wing arranged after the manner of a treble joint.

Fig. 2 is a similar view of an aeroplane

having the hull and wing disposed after the manner of a double joint.

Fig. 3 is a perspective diagrammatic view of a machine embodying the constructive features disclosed in Fig. 2. 60

Fig. 4 is a diagrammatic section of an aeroplane of a similar kind in which the strut bracing serves for stiffening the hull.

Fig. 5 is a perspective diagrammatic view of a machine embodying the constructive 65 features disclosed in Fig. 4.

Figs. 6 and 7 are diagrammatic sections of two further modifications.

Referring first to Fig. 1 of the drawings, 1 is the front portion and 2 the rear portion 70 of the hull which are united below the wing 3 by means of the joint 4, further joints 5 and 6 being formed between these parts of the hull and the wing. The members 7 and 8 bridging the span between the hull and 75 the wing may either be fins or strut bracings having rigid bases at the hull or at the wing or at both these parts. Thus, in Fig. 1 the forward end of the bracing is rigidly fixed to the rigid front portion of the wing, 80 while the rear portion of the wing, which is less rigid, is connected by means of the joint 6 to the strut bracing 8 having its basis at the rigid rear portion of the hull.

As shown in the drawings, the three 85 parts 1, 2, 3 form in the vertical longitudinal plane a statically defined three-joint system which, in spite of the large opening in the hull, is capable of taking up all the forces acting in this plane, which originate 90 from loads, from the air resistance acting on the wing and rudders and from the motor.

In the modification illustrated in Fig. 2, 95 the hull is not made in two separate parts, but has front and rear portions are directly connected with one another by a bottom portion 9. From a practical standpoint this arrangement is simpler, inasmuch as the assembling and handling of the body is simplified. The conditions of resistivity are not materially changed, because, in consequence of the static over-definition resulting from the bottom portion 9 which does not altogether act like a joint, no fundamental 100 displacement of forces takes place.

In the machine disclosed in Fig. 3, besides the bottom 10 of the hull, which is triangular in cross-section, only one side wall 11 is uninterrupted, while the cover is interrupt-

ed by a large opening, the other side wall by a triangular indenture designed for the door 12. The two forward strut bracings 7 which are rigid in all directions, are formed 5 each of three struts arranged in pyramids having their bases on the wing, while their points 5 form a rigid joint axis near the hull. The two rear strut bracings 8 are formed by two triangles disposed in parallel 10 longitudinal planes with their bases fixed to the hull, while their points 6 are linked to the wing in a transverse plane and adapt themselves to the wing which is already fixed relatively to the hull by the front 15 struts 7. In this arrangement, wherein the weakened middle portion of the hull can be regarded statically as a ball joint, the joint axes formed by the ends 5-5 and 6-6, respectively, of the struts connect the forward 20 and rear portions of the hull with the middle wing portion, all of which are safe against torsional stresses, in a manner which renders also the structure resulting from their combination safe against torsional 25 stresses.

If the front and rear portions of the hull are connected with each other in the above manner, for instance after the manner of a transversely disposed joint axle, one of them 30 can be connected with the wing after the manner of a ball joint, that is by means of a single triangle of struts. Bending stresses acting on the hull in the horizontal plane are also transmitted by the joints, partly 35 in combination with torsional forces, onto the middle wing portion.

The door 12 has a top-beam 13 adapted to be rigidly connected with the side wall by means of fixation not shown in the drawing, the closed door thus forming a continuation of the hull structure and transmitting tensile and compressive forces. During flight the elastic changes of form of the hull, quite especially those occasioned by forces 40 arising from lateral steering, are lessened, while at the bottom the hull can be handled after the wing has been completely dismounted. During normal service the middle portion 3 of the wing is permanently 45 connected to the hull, only the lateral wing portions 14, 15 being arranged to be removed for transport.

In order to safeguard the hull against heavy tensile stresses, the carriage is so designed 50 that the forces transmitted through it are directly transferred onto the joints connecting the wing and the hull. To this end the carriage struts 16 carrying the load extend from the wheel axle 17 directly to the joints 5 of the strut bracings 7. The links 18 which are merely placed under minor stresses and the struts 19 serving to support the middle portion of the axle are connected with other parts of the hull structure. 55

In the aeroplane illustrated in Figs. 4 and 5, the rear portion 2 of the hull has rigid fins or bracing towers 7 which are connected with the front portion 1 by two struts 20, the two portions of the hull being connected 60 by the joint 4. In this arrangement, the hull is well braced while large spaces are available in its interior and sufficiently wide openings in the side walls. The wing 3 is either merely provided with the necessary 65 means of connection in at least three points, for instance by adding a transverse triangle of struts 21, or it can be utilized for further bracing the hull, more especially 70 against torsional stresses, by arranging further strut bracings. 75

Without departing from the spirit of this invention, the joints above mentioned can be designed after the manner of rigid bracings, such as used in framework assemblage 80 points, as is the case for instance at 9 in Fig. 2.

As shown in Fig. 6, the new type of aeroplane above described can also be provided with several wings, for instance by arranging 85 a lower bearing plane 25 below the bottom of the hull.

The carriage may as well be replaced by floats 26 as shown by way of example in 90 Fig. 7.

I wish it to be understood that I do not desire to be limited to the exact details of construction shown and described, for obvious modifications will occur to a person skilled in the art. 95

I claim:—

1. Flying machine comprising a hull and a wing placed across and at a distance from said hull, a side wall of said hull having a large indentation, and a strut bracing 105 connecting said hull and said wing and forming a rigid connection of the parts of the hull structure which are interrupted by said indentation.

2. Flying machine comprising a hull, a side wall of said hull having a large indentation open on top; a wing and a strut bracing connecting the middle portion of said wing with the front portion and with the rear portion of said hull, while leaving the 110 middle portion of said hull practically unobstructed.

3. Flying machine comprising a hull, a side wall of said hull having a large indentation open on top, a wing and a strut bracing connecting the middle portion of said wing with the front portion and with the rear portion of said hull, while leaving the middle portion of said hull practically unobstructed, said front and rear portions and 115 said strut bracing constituting a rigid three-joint structure.

4. Flying machine comprising a hull, a side wall of said hull having a large indentation open on top, a wing and a strut brac- 120

ing connecting the middle portion of said wing with the front portion and with the rear portion of said hull, while leaving the middle portion of said hull practically unobstructed, said front and rear portions, said wing and said strut bracing constituting a rigid three-joint structure.

5. An aeroplane comprising a hull, a side wall of said hull having a large indentation open on top, and a wing, the front and rear portions of said hull being formed rigid against torsional stresses, and a front and a rear system of strut bracings connecting said wing to said hull and arranged to form a member rigid against torsional stresses.

6. An aeroplane comprising a hull, a side wall of said hull having a large indentation open on top; and a wing, the front and rear portions of said hull being formed rigid against torsional stresses and a pair of strut bracings which are arranged in a transverse joint axle and connect each portion with said wing.

7. An aeroplane comprising a hull, a side wall of said hull having a large indentation open on top, and a wing, the front and rear portion of said hull having triangular cross section and being formed rigid against torsional stresses, and a front and a rear system of strut bracings connecting said wing to said hull and arranged to form a member rigid against torsional stresses.

8. An aeroplane comprising a hull and a wing, the front and rear portions of said hull being formed rigid against torsional stresses and being connected at least in one point, two strut bracings rigid in all directions connecting the wing with one of said portions and two strut bracings rigid in the longitudinal direction connecting said wing with the other portion.

9. An aeroplane comprising a hull and a wing, the front and rear portions of said hull being formed rigid against torsional stresses and being connected at least in one

point, two strut bracings rigid in all directions connecting the wing with one of said portions and two strut bracings rigid in the longitudinal direction connecting said wing with the other portion, said forward strut 50 bracings being rigidly fixed by their bases to the wing, their points being linked to the front portion of the hull, while the rear strut bracings have their bases rigidly connected to the rear portion of the hull, their 55 points being linked to said wing.

10. Flying machine comprising a hull and a wing placed across and at a distance from said hull, a side wall of said hull having a large indentation open on top and a strut 60 bracing connecting said hull and said wing and forming a rigid connection of the parts of the hull structure which are interrupted by said indentation, a door arranged in said indentation and a top beam on said door 65 statically structurally supplementing the missing portion of said wall.

11. Flying machine comprising a hull, a wing and a strut bracing connecting the middle portion of said wing with the front 70 portion and with the rear portion of said hull while leaving the middle portion of said hull practically unobstructed, a carriage below said hull and struts connecting said carriage with the strut bracings 75 connecting the hull with the middle portion of said wing.

12. Flying machine comprising a hull, a wing and a strut bracing connecting the middle portion of said wing with the front 80 portion and with the rear portion of said hull while leaving the middle portion of said hull practically unobstructed, a carriage below said hull and struts connecting said carriage with the strut bracings 85 connecting the middle portion of said wing with said hull.

In testimony whereof I affix my signature.

HUGO JUNKERS.
